UNITED STATES PATENT OFFICE.

FRANK S. SHEFFLER, OF NEW CASTLE, PENNSYLVANIA.

CAR-COUPING.

1,317,598.

Specification of Letters Patent. Patented Sept. 30, 1919.

Application filed July 3, 1918. Serial No. 243,224.

To all whom it may concern:

Be it known that I, FRANK S. SHEFFLER, a citizen of the United States, residing at New Castle, in the county of Lawrence and 5 State of Pennsylvania, have invented certain new and useful Improvements in Car-Couplings; and I do declare the following to be a full, clear, and exact description of the invention, such as will enable others 10 skilled in the art to which it appertains to make and use the same.

The present invention relates to improvements over U. S. Patent No. 781,791, issued February 7, 1905, to myself and C. S. 15 Turner.

The objects of the improvements are principally as follows:

First, to provide a coupler which will not re-couple after being cut or uncoupled, in 20 case it is again forced against the coupler of another car;

Second, to provide a construction which will couple or lock even though the cars be brought together on sharp curves or at high 25 speed;

Third, to provide means for relieving the knuckle pivot pin of practically all strain; and

Fourth, to provide a coupler which will 30 require little attention and will not necessitate the trainmen riding the cars or running alongside as is now necessary.

With the foregoing general objects in view the invention resides in the novel features 35 of construction and unique combinations of parts to be hereinafter fully described and claimed, the descriptive matter being supplemented by the accompanying drawings which form a part of this specification and 40 in which:

Figures 1 and 2 are perspective views of the improved coupler in operative position, looking in different directions;

Fig. 3 is a duplicate of Fig. 1 with the 45 exception that it shows the coupler and knuckle in open position and the locking pin supported free of said knuckle;

Fig. 4 is a perspective view of the coupler head; and

50 Fig. 5 is a perspective view of the knuckle;

Fig. 6 is a detail perspective view showing the manner in which the locking pin may drop to an operative position when 55 coupling at high speed;

Fig. 7 is a perspective view of the locking pin;

Fig. 8 is a top plan view of the coupler with the upper section of the locking pin removed showing the manner in which the 60 hook-like tails of the knuckle clear the locking pin;

Fig. 9 is a view similar to Fig. 8 with the knuckle locked in closed position;

Fig. 10 is a longitudinal section as indicated by the line 10—10 of Fig. 8; and

Fig. 11 is a transverse section as indicated by the line 11—11 of Fig. 9.

In the drawings above briefly described, the numeral 1 designates any preferred type 70 of draw bar having a coupler head 2 integral with its front end and of substantially the same type shown in the patent above referred to. The knuckle 3 is provided with upper and lower hook-like tails 4 which lie 75 upon the upper and lower sides of the head 2 and are pivoted thereto by a pivot pin 5. When the knuckle is closed, the lateral ends 6 of the tails 4 abut the rear sides of upper and lower abutments 7 which are cast integrally with the head 2 and thus practically all strain is relieved from the pivot pin 5.

To obviate the necessity of the trainmen opening the knuckle 3 by hand as is now often necessary, a suitable spring 8 is secured at 9 to the head 2, said spring being received at its free end in a recess 10 in the inner side of the knuckle and operating to maintain said knuckle in opened position until it is closed by bringing two cars together. The opening movement of the knuckle is limited by a vertical stop rib 11 formed integrally with the head 2 (see full lines of Figs. 4 and 9, and dotted lines of Fig. 8). 95

For holding the knuckles 3 in closed position, a vertical locking pin 12 is mounted slidably in a guide-way 13 formed in the central portion of the head 2, the upper end of said pin having a laterally extending 100 head 14 adapted to abut the head 2 to limit the downward movement of the pin and also to rest upon the lateral end 6 of the upper tail 4 when the knuckle is opened, so that closing of this knuckle will permit the pin to drop by gravity to operative position. When coupling at high speed, it often happens that the knuckle is closed so quickly and then again moved outwardly by recoil, that the locking pin 12 cannot 110

drop to the full extent, but in order that this pin may even then become operative, the lower end of its head 14 is provided with a right angular notch 15 which receives the rear end of the upper tail 4 as illustrated fully in Fig. 6. When the pin 12 is raised, the beveled intermediate portion 16 thereof is so positioned as to permit the tails to clear said pin as will be clear from Figs. 8 and 9, this construction being very similar to that shown in the patent above mentioned.

In order that the pin 12 may be held in raised position so as not to drop in place until required, the rear side of its head 14 is provided with a hook-like rib 17 to engage a similar rib 18 formed across the coupler head 2 at the rear side of the guideway 13; and in order that the upper end 20 of the pin may move rearwardly to a sufficient extent to interengage the two ribs, said pin is formed of upper and lower sections pivotally united by a link 19 received in slots 20 in the adjacent ends of said sections. A chain 21 is shown rising from the front portion of the head 14 for connection with the usual means for raising the locking pin, and due to the fact that the chain inclines rearwardly to a slight extent from the pin, it will shift the upper end of said pin rearwardly when the pin is raised, to properly seat the rib 17 upon the corresponding rib 18. The locking pin 12 is thus held in a raised position and consequently even though the knuckle 3 be closed a number of times by contact with other cars, after the coupler has been released, said knuckle will not lock in its closed position. When two cars are to be coupled, the ribs 17 and 18 are disengaged manually and the lateral head 14 permitted to rest upon the end 6 of the upper knuckle tail 4 with the knuckle in open position. It thus follows that when this knuckle is closed by contact with the other coupler, the pin 12 is permitted to drop by gravity to an operative position, in which position both tails 4 contact with the pin. It often happens that when coupling on sharp curves, the knuckle is not forced inwardly to such an extent as to permit the pin to drop when the usual construction is employed. This has been taken care of however by the provision of the notch 15 which allows the pin to lower sufficiently to become effective, even though the knuckle is not entirely closed. The notch in question is also of advantage in permitting the pin to drop at least part way before recoil of the knuckle takes when coupling at high speed.

From the foregoing, taken in connection with the accompanying drawings, it will be obvious that I have provided compara-

tively simple means for carrying out the objects of the invention; and since probably the best results are obtained from the details shown and described, they are by preference employed, but within the scope of the invention as claimed, numerous minor changes may well be made.

I claim:

1. A car coupler comprising a forked head having one arm relatively narrow in a vertical direction, said head equaling said relatively narrow arm in width at its junction therewith and having an opening leading through both its top and bottom, the portion of the head directly in rear of said opening extending above said narrow arm and having a transverse upstanding flange, a knuckle having upper and lower parallel arms straddling said relatively narrow arm of said head and pivoted thereto, the upper arm of said knuckle having a lateral tail, a locking pin vertically slidable in said opening and bearing against the end of the lower arm when the coupler is locked, the upper end of said pin having a head which extends laterally therefrom to abut the end of the upper arm when the coupler is locked and to rest on said tail when the coupler is set for connection with another coupler, said head also extending from said pin in another direction and being here shaped to form a hook-like rib adapted to hook over the aforesaid flange to retain the pin in released position when it is manually raised to move its lower end and its head free of said knuckle arms, said pin being formed of upper and lower sections linked together to permit engagement of said rib and flange, the lower side of said head having a notch to receive the end of the upper knuckle arm when rapid rebound of or insufficient closing of the knuckle does not permit full dropping of the pin.

2. A car coupler comprising a forked head having one arm relatively narrow in a vertical direction, a knuckle having parallel arms straddling and pivoted to said narrow arm, means for locking said knuckle, a spring secured to said narrow arm and bearing against said knuckle to open the latter when said locking means is released, and a vertical rib on the outer side of said narrow arm to limit the opening of said knuckle.

In testimony whereof I have hereunto set my hand in the presence of two subscribing witnesses.

FRANK S. SHEFFLER.
